UNITED STATES PATENT OFFICE.

WILLIAM BERNARD AND LEO FRANK, OF NEW YORK, N. Y.

DESIGN FOR A CIGAR ASH RECEPTACLE, &c.

SPECIFICATION forming part of Design No. 22,872, dated November 7, 1893.

Application filed April 26, 1893. Serial No. 471,884. Term of patent 7 years.

To all whom it may concern:

Be it known that we, WILLIAM BERNARD and LEO FRANK, citizens of the United States, residing in the city, county, and State of New York, have invented and produced a new and original Design for a Cigar and Ash Receptacle, of which the following is a specification, reference being had to the accompanying drawings, forming a part thereof, and in which—

Figure 1 is a top view of the receptacle, and Fig. 2. is a sectional view of the same on the line *x x* of Fig. 1.

The leading features of our design consist of the shape of the body of the receptacle and the ornamental configuration of the rim thereof as illustrated in the drawings.

The receptacle consists of the bowl portion

B. and the rim C. The rim is composed of the radial groove A. extending out from the bowl portion B. Alternating with these grooves are the intermediate conventionalized foliate scrolls D which connect said grooves and therewith form the general outline of the rim.

What we claim is—

The design for a cigar and ash receptacle, or other plate substantially as herein shown and described.

In witness whereof we have hereunto set our hands.

WILLIAM BERNARD.
LEO FRANK.

Witnesses:

GEORGE W. CHESTER,
GEO. O. ROMBE.
